UNITED STATES PATENT OFFICE.

JOHN WOJCIK, OF CHICAGO, ILLINOIS.

LOCK.

1,374,793.

Specification of Letters Patent. Patented Apr. 12, 1921.

Application filed November 12, 1920. Serial No. 423,579.

To all whom it may concern:

Be it known that I, JOHN WOJCIK, citizen of Poland, residing at Chicago, in the county of Cook and State of Illinois, have 5 invented certain new and useful Improvements in Locks, of which the following is a specification.

This invention relates to certain new and useful improvements in locks and has for 10 one of its objects to provide a sliding gravity bolt within the lock casing adapted for engagement with a keeper bolt when the same is in its lowered closed position.

A further object of the invention is to 15 provide a lock embodying a gravity bolt slideable within the casing and adapted to be elevated through the medium of a key inserted within the lock casing while a gear within the lock casing is adapted to have 20 rack teeth of the gravity bolt moved into engagement therewith for sliding the bolt within the casing to move the same to its released position.

With the above and other objects in view, 25 the present invention consists in the novel form, combination and arrangement of parts hereinafter more fully described in connection with the accompanying drawings, in which like reference characters in- 30 dicate similar parts throughout the several views.

In the drawings,

Figure 1 is a fragmentary elevational view of a portion of a door and frame with 35 the present improved lock operatively positioned thereon,

Fig. 2 is a view similar to Fig. 1 with the lock casing removed showing the sliding gravity bolt with the bolt elevated in dotted 40 line positions for engagement with the shifting gear,

Fig. 3 is a cross sectional view taken on line III—III of Fig. 2 showing the rotatable gear for shifting the slideable gravity bolt,

Fig. 4 is a cross sectional view taken on line IV—IV of Fig. 2 showing the key elevating the bolt to engaging position with the shifting gear,

Fig. 5 is a perspective view of the gravity sliding bolt removed from the casing,

Fig. 6 shows views of the key for elevating the sliding bolt, and

Fig. 7 shows views of the key for rotating the gear shifting the sliding bolt.

Referring more in detail to the accom-

panying drawings, there is illustrated the portion of a door 1 and frame 2 upon the inner face of which door a lock casing 3 is mounted while a keeper casing 4 is mounted upon the door frame 2 and secured thereto by a bolt 5 extending through the casing and door frame. The lock casing 3 is secured to the door 1 by transverse bolts 6 and upper and lower bolts 7 at the swinging 60 end of the door, a face plate 8 being secured to the outer side of the door as shown in Figs. 1 and 3.

A gravity sliding bolt of the type more clearly shown in Figs. 2 and 5 embodies a 70 body portion 9 having a hook nose 10 at its forward end while the upper edge thereof is provided with a series of rack teeth 11. A pair of elongated openings 12 is provided in the bolt body 9 with an upwardly directed offset recess 13 at the rear ends thereof. The bolt 9 within the casing 3 is supported on the transverse supporting bolts 6 as shown in Fig. 2.

The lower wall of the casing 3 is provided with a downwardly directed arcuate extension 14 through which an angle key opening 15 extends. For elevating the bolt within the casing, the key shown in Fig. 6 is employed, the same embodying a finger grip 75 16 having a shank 17 with angularly extending head portions 18 and 19, the latter being notched at its edge as at 20 as clearly shown in Figs. 4 and 6. When the bolt 9 is in the position shown in Fig. 2, the same 80 is at its limit of downward movement with the transverse bolts 16 received in the slot recesses 13 while the hook nose 10 is in engagement with the bolt 5 in the keeper casing 4. When the key 16 is inserted through 85 the key slot 15 and rotated the head portion 19 thereof is projected to cause the notched end thereof to inclose the lower edge of the bolt 9 and to elevate the same to the dotted line position shown in Fig. 2, thereby positioning the connecting bolts 6 in the elongated slots or openings 12.

To provide for a sliding movement of the bolt within the casing 6 to remove the forward end thereof from the keeper casing 4 100 a gear 21 is journaled within the casing 3 within the casing enlargement 22 as shown in Fig. 2 upon a tubular bearing 23 having a rectangular bore within which the key 24 shown in Fig. 7 is adapted to be inserted for 105 rotating the gear. The door 1 is provided with an opening 25 to facilitate insertion

of the key 24 within the lock casing as illustrated in Fig. 4 for rotating the gear 21. When the key 16 elevates the bolt 9 to the dotted line position shown in Fig. 2, the 5 rack teeth 11 of the bolt are moved into engagement with the gear 21, and by rotating the gear in the desired direction, the bolt is shifted in a similar way, either to withdraw the bolt into the casing 3 or project the same 10 into the keeper casing 4.

A key hole guard is associated with the key opening 15 extending through the face plate 8 of the door 1 and embodies an angle bracket 26 and a swinging plate 27 having 15 coöperating flanges 28 through which the shackle 29 of a padlock extends, thereby closing the key opening 15 as shown in Fig. 1.

Assuming that the sliding gravity bolt is 20 in the locked position shown in Fig. 2, and it being desired to free the same from engagement with the keeper bolt 5, the key 16 is inserted in the opening 15 and rotated to cause the angle head 19 thereof to engage 25 the lower edge of the bolt to elevate the same to position the attaching bolts 6 within the elongated openings 12. The key 24 inserted into the bearing 23 of the gear 21 is rotated and by meshing with the rack 30 teeth 11 upon the sliding bolt, the bolt 9 is withdrawn into the casing 3. In shifting the bolt to locked position, the key 16 may be withdrawn from the casing 3 and the rack gear 21 rotated to project the bolt 35 from the casing 3 and when the offset recesses 13 of the openings 12 are positioned over the bolts 6, the sliding bolt 9 will drop by gravity with the hook nose 10 thereof engaging the keeper bolt 5 while the bolts 6 40 are received in the bolt recesses 13. The padlock 29 associated with the guard plate 27 prevents the operation of the lock from the outer side of the door without first exposing the key hole.

45 While there is herein shown and described the preferred embodiment of the invention, it is nevertheless to be understood that minor changes may be made therein without departing from the spirit and scope of the 50 invention as claimed.

What is claimed as new is:

1. A lock of the type described comprising a casing, a gravity sliding bolt mounted therein, said bolt having elongated slots and

offset recesses communicating with the slots, 55 transverse bolts carried by the casing for supporting the bolt and extending through said slots, a key for elevating the sliding bolt to position the transverse bolts in the elongated slots, rack teeth formed on the 60 upper edge of said bolt and a rotatable gear carried by said casing adapted for engagement with the bolt rack teeth for shifting the bolt within the casing.

2. A lock of the type described comprising 65 a casing, a gravity sliding bolt mounted therein, said bolt having elongated slots and offset recesses communicating with the slots, transverse bolts carried by the casing for supporting the bolt and extending through 70 said slots, a key for elevating the sliding bolt to position the transverse bolts in the elongated slots, rack teeth formed on the upper edge of said bolt, a rotatable gear carried by said casing adapted for engagement with 75 the bolt rack teeth for shifting the bolt within the casing, a tubular bearing for said gear and a key inserted within said bearing for rotating the same.

3. A lock of the type described comprising 80 a casing, a gravity sliding bolt mounted therein, said bolt having elongated slots and offset recesses communicating with the slots, transverse bolts carried by the casing for supporting the bolt and extending through 85 said slots, a key for elevating the sliding bolt to position the transverse bolts in the elongated slots, rack teeth formed on the upper edge of said bolt, a rotatable gear carried by said casing adapted for engagement 90 with the bolt rack teeth for shifting the bolt within the casing, a tubular bearing for said gear, a key inserted within said bearing for rotating the same and a hinged guard plate overlying the key opening 95 through which the key is inserted for elevating the sliding bolt.

4. A lock of the type described comprising 100 a casing, a gravity sliding bolt mounted therein, coöperating means carried by the bolt and casing for holding the bolt in locked position, means for elevating the bolt to render ineffective the means for holding the same locked and coöperating devices carried by the casing and bolt for shifting 105 the bolt within the casing.

In testimony whereof I affix my signature.
JOHN WOJCIK.
